EMIL GAIRING, OF DETROIT, MICHIGAN, ASSIGNOR TO GAIRING TOOL COMPANY, OF DETROIT, MICHIGAN, A CORPORATION OF MICHIGAN.

DEVICE FOR EXHIBITING TOOLS.

Application filed January 3, 1927. Serial No. 158,518.

My invention relates to a device for exhibiting metal working tools, particularly boring or like tools, shown in the accompanying drawings and more particularly described in the following specification and claims.

The primary object of my invention is to provide a device which is adapted to make a pleasing and interesting display for window or exposition purposes of a plurality of tools with means for rotating the same, showing the cutting end of the tool inserted in a block as if in the act of boring, counter-boring or spotfacing, the construction being such that any of the tools may be manually held against rotation while operating for closer inspection without interfering with the rotation of the remaining tools,—or any of the tools may be removed and replaced by tools fitted with longer or shorter shanks or replaced by other tools as may be desired.

A further object of the invention is to show the wood or metal elements operated upon by the tool in cross-section, that the cutting end of the tool may be seen in operation with a profile of the cut made thereby.

With the foregoing and other objects in view which will appear as the description proceeds, the invention further resides in the details of construction hereinafter described and claimed, it being understood that changes may be made in the precise embodiment of the invention herein disclosed without departing from the spirit of the same.

In the drawings accompanying this specification:

Figure 1 is a perspective view of the tool supporting stand, showing a plurality of tools rotating in elements representing the wood or metal being machined thereby,—said elements being in cross-section and shaped to indicate the cut made by the respective tools.

Figure 2 is an end elevation and cross-sectional view, with parts broken away, showing the manner of supporting and driving the respective tools.

Figure 3 is a fragmentary plan and horizontal sectional view through the hollow base, with a prime mover and driving shaft housed therein to actuate the several tools.

Figure 4 is a fragmentary side elevation

and longitudinal sectional view taken on or about line 4—4 of Figure 3, showing the motor, the driving shaft actuated by the motor and the driving connection between the shaft and the spindles for operating the several tools.

Figure 5 is a detailed cross-sectional view taken on or about line 5—5 of Figure 2 showing the means for locking a supporting pin projecting from the end of one of the tools in driving connection with one of the spindles rotated by the driving shaft.

Referring now to the letters of reference placed upon the drawings:

A denotes a chambered base fitted at the rear with a removable plate B whereby access may be gained to the interior of the base. C is an electric motor or other prime mover bolted to the lower floor plate A¹ of the base. C¹ is the projecting end of the armature shaft of the motor journaled in the bearings C² bolted to the floor plate. D is a pinion keyed to the armature shaft in mesh with a gear E carried by a driving shaft F, journaled in bearing G, G¹ bolted to the lower floor plate. Keyed to the driving shaft F and in spaced relation to each other is a plurality of worm-gears H respectively in mesh with a plurality of worm-gears I, loosely mounted upon vertically disposed spindles J, having their upper ends journaled in sleeves K supported in annular bosses A² integral with the upper floor plate A³ of the chambered base. The sleeves K have a flange K¹ overlapping the annular bosses on the upper face of the floor plate and a tapering cone-shaped end K², to receive the ends of the respective tools Z.

Axially supported in the end of each of the tools by a set screw L¹, or other fastening means, is a rod L extending downwardly through the sleeve K into the spindle J,—the lower end of the rod L being flattened as at L² that it may pass a transverse pin J¹ extending through the spindle and whereby a locking engagement is obtained between the spindle and pin to provide a driving connection with the tool Z, to rotate the latter.

The tools Z are supported vertically at their upper ends by the adjustable arms M, sleeved upon upright rods N rising from the chambered base. The outer end of the arms M are provided with tapering pins M¹

screwed into the end of the arms—the pointed end of the pin entering a tapering axial recess in the end of the tool shank.

M^b is a set screw in the hub of the adjustable swinging arms M to secure it in fixed relation to the upright posts N when properly adjusted. P denotes one or more wood or metal elements secured to the upper floor plate of the chambered base with sockets corresponding to the cut of the respective tools into which the cutting end of the latter projects. The socket however is shown as in "section" in order that an observer may see the profile of the cut made by the tool and the position of the tool in relation to the cut when in operation.

Q is a friction clutch disc bolted to the hub of the worm-gear I , in turn sleeved upon the vertically disposed spindles. This disc on its face is provided with a felt or other washer Q^1 to insure frictional driving relation between it and a co-operating disc Q^a , secured by a transverse pin Q^2 extending through a slot Q^3 in the spindles. The lower end of the spindles are supported upon blocks R , projecting from a recess in the floor plate which may be adjusted by a screw threaded bolt R^1 extending through the floor.

Screwed upon the end of the spindles are nuts S , which bear against a washer S^1 and upon adjusting the nut a spring T , sleeved on the spindle and bearing against the hub of the disc Q^a may be put under more or less tension. U is an electric light bulb supported in the base plate, concealed by an overlapping flange A^4 of arc-shaped form which serves also as a reflector to direct the rays of light toward the several tools.

W denotes a panel raised in the wall of the base to receive the name of the manufacturer—or data relating to the tools displayed, or both.

Having indicated the several parts by reference letters, the construction and operation of the device will be readily understood.

The motor having been connected through service wires in the usual way to a source of electrical energy, upon starting the motor the driving shaft F is actuated through the gearing D and E . The driving shaft F , fitted with its several worm-gears in mesh with like gears mounted upon the respective spindles J , serves through the pins K , projecting from the ends of the cutting tools to rotate the tools supported upon the adjustable bracket arms M in a manner simulating the operation of said tool when in actual working operation.

The ends of the cutting tools project into sockets in cross-section and show the profile of the cut made by the respective tools when under actual working conditions.

If an observer desires to arrest the rotation of a tool to particularly inspect the same, he may do so by grasping the tool

while it is rotating, whereupon the spring clutch Q releases the tool from driving connection without interfering with the rotation of the other tools. Immediately however upon releasing the tool the friction clutch Q again engages, causing the tool to operate as before.

Having thus described my invention what I claim is:

1. In a device of the character described, a supporting frame; a prime mover housed in the supporting frame; a driving shaft actuated by the prime mover; a plurality of gears mounted in spaced relation on the driving shaft; a plurality of vertical spindles suitably journaled fitted with gears respectively in mesh with the gears on the driving shaft; a plurality of cutting tools supported in axial alignment with the spindles adapted to rotate therewith but held against longitudinal movement, whereby they may simulate the cutting operation of a plurality of tools under actual working conditions; and means adapted to provide a driving connection between the gears and spindles but which is also adapted upon manually holding any of the tools against rotation to automatically release the corresponding operating spindle of the tool from rotation by the driving shaft, whereby the remaining spindles may continue to operate without interference.

2. In a device of the character described, a supporting frame; a prime mover housed in the supporting frame; a driving shaft actuated by the prime mover; a plurality of gears mounted in spaced relation on the driving shaft; a plurality of vertical spindles suitably journaled fitted with gears respectively in mesh with the gears on the driving shaft; a plurality of cutting tools rotated by said spindles but held against longitudinal movement, whereby they may simulate the cutting operation of the tool without actually working under operating conditions; a plurality of friction clutches adapted to provide a driving connection between the gears and spindles, whereby upon manually holding any of the tools against rotation the corresponding spindle supporting the tool may be released from driving relation with the driving shaft that the remaining spindles may continue to rotate without interference; means for maintaining the tools in axial alignment with said spindles; and a cross-sectional element in profile provided with sockets adapted to receive the cutting end of said tools, conforming to the resulting cutting action of the tool, whereby the tool when rotated will simulate its proper cutting operation.

3. In a device of the character described, a supporting frame; a prime mover housed in the supporting frame; a driving shaft actuated by the prime mover; a plurality of

- gears keyed in spaced relation to the driving shaft; a plurality of sleeves supported in the frame in spaced relation to each other; a plurality of vertically disposed spindles respectively journalled in the sleeves; a plurality of gears loosely mounted upon the spindles in mesh with the gears of the driving shaft; a plurality of cutting tools adapted to be rotated by the spindles but held against movement, whereby they may rotate to simulate the operation of the tools without longitudinal movement for performing a cutting operation; a plurality of friction clutches, comprising a fixed and a movable member, one member of each clutch being bolted to the gears sleeved upon the respective spindles, the other member being loosely engaged to the spindles; springs sleeved upon the spindles and bearing against the last named member of the clutch to force it into driving engagement with the first named member; and nuts screwed to the end of the spindles and against the end of the springs to adjust the tension of said springs.
4. In a device of the character described, a supporting frame; a prime mover housed in the supporting frame; a driving shaft actuated by the prime mover; a plurality of gears keyed in spaced relation to the driving shaft; a plurality of sleeves supported in the frame in spaced relation to each other; a plurality of vertically disposed spindles respectively journalled in the sleeves; a plurality of cutting tools supported upon the end of the respective sleeves; a plurality of gears loosely mounted upon the spindles in mesh with the gears of the driving shaft; a plurality of rods respectively extending into each of the tools and secured thereto and extending through the sleeves into the end of the spindles, said rods being respectively flattened at the end extending into the spindles; and a transverse pin projecting through the spindles and overlapping the flattened portion of the pin to provide a driving connection between the spindle and the tool, whereby said tools may be rotated to simulate a cutting operation without actually performing such operation.
5. In a device of the character described, a supporting frame; a prime mover housed in the supporting frame; a driving shaft actuated by the prime mover; a plurality of gears keyed in spaced relation to the driving shaft; a plurality of sleeves supported in the frame in spaced relation to each other; a plurality of vertically disposed spindles respectively journalled in the sleeves; a plurality of gears loosely mounted upon the spindles in mesh with the gears of the driving shaft; a plurality of tools supported upon the end of the respective sleeves adapted to be rotated without longitudinal movement, whereby they may simulate the operation of the tools under working conditions without performing a cutting operation; a plurality of friction clutches providing a driving connection between the gears and spindles, comprising a fixed member secured to the gears and a movable member secured to the spindles; springs sleeved upon the spindles bearing upon the movable member of the clutch connected therewith to force it into driving engagement with the fixed member secured to the gears; and nuts screwed to the end of the spindles adapted to adjust the tension of the springs.
6. In a device of the character described, a supporting frame; a prime mover housed in the supporting frame; a driving shaft actuated by the prime mover; a plurality of gears mounted in spaced relation on the driving shaft; a plurality of vertical spindles suitably journalled and fitted with gears respectively in mesh with the gears on the driving shaft; a plurality of tools supported by the respective spindles and rotated thereby; a plurality of upstanding rods; a plurality of swinging arms adjustably secured to said rods and fitted at their free end with adjustable pivot pins adapted to engage the end of the tools, said pins being in axial alignment with the respective spindles; a plurality of friction clutches adapted to provide a driving connection between the gears and spindles whereby upon manually holding any of the tools against rotation to release said tool spindle from rotation by the driving shaft, whereby the remaining spindles with their respective tools may continue to operate without interference.
7. In a device of the character described, a supporting frame provided with a chambered base; a prime mover housed in the chambered base; a door for closing an opening into said base; a driving shaft actuated by the prime mover; a plurality of gears mounted in spaced relation on the driving shaft; a plurality of vertical spindles suitably journalled and fitted with gears respectively in mesh with the gears on the driving shaft; a plurality of tools respectively rotated by the spindles; a plurality of rods rising from the base; a plurality of swinging arms adjustably mounted upon said rods adapted to support the upper end of the tool shanks supported by the spindles; and a plurality of friction clutches, adapted to provide a driving connection between the gears and spindles whereby upon manually holding any of the tools against rotation the operating spindle of the tool held may be released from rotation that the remaining spindles with their respective tools may continue to operate without interference.
8. In a device of the character described, a supporting frame; a prime mover housed in

the supporting frame; a driving shaft actuated by the prime mover; a plurality of rotatable cutting tools; means for supporting said cutting tools in spaced relation to each other; an element provided with sockets to receive the cutting end of said tools, said element being divided longitudinally in cross-section through the sockets, whereby the rotation of the tools may be observed in the sockets provided in the element to receive it; means actuated by the prime mover

for rotating while resisting longitudinal movement of the cutting tools, whereby the tools when actuated may simulate their operation under actual working conditions without cutting; and means whereby one or more of said tools may be manually held against rotation for inspection without arresting the operation of the remaining tools.

In testimony whereof, I sign this specification.

EMIL GAIRING.
